UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

MACHINE FOR SHAPING LIPPED SOLES.

Application filed November 29, 1924. Serial No. 752,988.

This invention relates to machines for operating upon lipped soles and is herein illustrated as embodied in a machine of the type disclosed in Letters Patent No. 1,574,794, granted March 2, 1926, in the name of the present inventor, for machines for shaping the lip and molding the feather at the toe of a reinforced insole of the Economy type. The illustrated machine, however, is also adapted to operate upon Gem insoles and upon various other types of lipped insoles such, for example, as leather insoles for Goodyear welt shoes and in various aspects the invention is not limited to embodiment in a machine of the illustrative type.

In the use of the machine illustrated in the patent just referred to, the lip of the sole is shaped to the desired contour and the feather is pressed against a flat sole support so that, in the completed sole, the feather lies in the plane of the body of the sole. In many instances, however, after shaping the lip to the desired predetermined contour at the toe in the machine above referred to, it has been found desirable to mold or break-down the feather at the toe of the sole so that it will hug the last more closely and thus render it easier for the operator to last the toe and to maintain the lip in proper relation to the channel guide during the operation of sewing the upper to the insole.

In view of the foregoing, one object of the present invention is to provide a machine for shaping the lip and molding the feather of a sole which will be so organized as to obviate the necessity of subjecting the sole to a further operation after the lip has been shaped for the purpose of molding or breaking-down the feather of the sole.

To this end, one feature of the invention consists in the provision, in a machine for operating upon lipped soles, of a form shaped to engage a substantial length of the lip and feather of a sole, and means constructed and arranged to co-operate with said form to shape the lip and offset the feather. In working out this feature of the invention, as herein illustrated, co-operating inner and outer lip shaping forms, such as

characterized the earlier machine above referred to, have been utilized, but the illustrative outer lip-engaging member is provided with a face inclined at the angle at which it is desired to offset the feather, and the sole support is provided with a plate or form having a beveled portion for co-operating with said face to offset or break-down the feather.

In the machine disclosed in the application above referred to, the lip is shaped between co-operating forms which have to be removed from the machine and replaced by co-operating forms of different shapes when soles of different styles are to be operated upon. In practice a single run of soles may include soles of several different styles and it is a further object of the present invention to reduce to a minimum the amount of time required to replace one set of co-operating forms with another so as to adapt the machine to operate upon soles of a different style.

With this object in view, and in accordance with a further feature of the present invention, quick-detachable connections of novel construction have been provided for securing both the lip-shaping and the feather-molding members in operative position in the machine.

The invention further consists in the features of construction and the arrangements and combinations of parts hereinafter described and claimed, the advantages of which will be obvious to those skilled in the art.

In the accompanying drawings, Fig. 1 is a view in vertical section of a machine constructed in accordance with the present invention;

Fig. 2 is a top plan view of the inner lip-shaping member;

Fig. 3 is a perspective view showing particularly the outer lip-shaping and feather-molding member and the quick-detachable connections for securing it to its support;

Fig. 4 is a front elevational view of a portion of the machine;

Fig. 5 is a side elevational view of the

operating instrumentalities of the machine showing them in operative relation to each other;

Fig. 6 is a detail sectional view showing 5 the operating instrumentalities and illustrating their mode of operation upon the work; and

Fig. 7 is a perspective view of the toe portion of a lipped insole which has been 10 operated upon in the present machine.

Referring to the drawings, the machine 15 therein shown comprises, in general, a head or frame 10; a work table 12 carried by the head 10 for supporting a sole while it is being operated upon; a feather molding block or form 14 carried by the work table for engaging the lower side of the feather of the sole; a form 16 for engaging the upper side 20 of the feather and the outer side of the lip and for co-operating with the block 14 to mold or offset the feather; a form 18 for 25 engaging the inner side of the lip and co-operating with the form 16 to shape the lip; vertically movable carriers or cylindrical 30 slides 20 and 22 for the forms 16 and 18 respectively; a slide 24 for imparting rearward movement to the carrier 22 and the form 18; a horizontal main shaft 26; and mechanism including the cam disk 28 on the 35 main shaft for actuating the carriers 20 and 22 and the slide 24.

Except as hereinafter described, the frame 10, the slides 20, 22 and 24, the means for supporting and guiding these slides and the 40 mechanism for actuating them are substantially the same in construction as corresponding parts described in the application above referred to and the same movements are imparted to the slides and to the forms 16 and 45 18 as in the machine of said patent. Consequently, it will be unnecessary to describe the construction or mounting of the slides or carriers or the operating mechanism therefor herein, reference being had to said application if desired for a detailed description thereof and of other parts not fully described herein.

Referring more particularly to Fig. 1, the work table 12 of the illustrative machine is 50 secured to a forwardly projecting portion of the head or frame 10 by means of screws such as that shown at 30, and is provided with two vertical dowel pins 32, 32 arranged to enter apertures 34, 34 in the feather molding block 14 detachably to secure the plate to the work table and accurately to locate the plate relatively to the forms 16 and 18.

The feather molding block or form 14 is 55 of the general triangular shape best shown in Fig. 3, the plate being formed with converging edge faces 36, 36 meeting at a point at the rear extremity of the plate and adapted to conform to the contour of the lip at the toe of a sole. The converging edge faces

36, 36 are also beveled or inclined transversely at the angle relatively to the plane of the work table at which it is desired to bend the feather. As shown, the third edge face of the block 14 is also beveled, as at 38, to facilitate the placing of a sole in position to 60 be operated upon by the block 14 and the forms 16 and 18. Notches 40, 40 are formed in the beveled edge face 38 adjacent to the bottom of the block to receive a screw driver or like tool which may be used to lift the 65 block or form 14 from the dowel pins 32, 32 when it is desired to remove the block. By locating the notches 40, 40 at opposite sides of a line extending through the apertures 34, 34 as shown, the screw driver or other 70 tool may be used most effectively to pry the block or form 14 from the dowel pins. As shown in the drawings, relatively sharp corners are formed at the junctions of the beveled edge faces with the flat upper face 75 thereof, this construction causing a sharp line of demarcation to be formed upon the lower face of a sole operated upon thereby between the molded feather and the body 80 of the sole. Such a sharp line of demarcation may be avoided if desired by rounding 85 the corners of the edge faces of the upper face of the block or form 14.

The form 16, as hereinbefore mentioned, is 90 adapted to co-operate with the block 14 to 95 mold the feather, and to cooperate with the form 18 to shape the lip. To adapt it for these purposes the form 16 is provided with a central V-shaped notch 42 providing opposite walls for engaging the feather and the lip at opposite sides of the toe. The lower portions of the walls formed by the notch 42 are inclined transversely, as shown at 95 44 in planes parallel to the beveled faces 34, 34 of the block 14, thus providing molding 100 faces complementary to the molding faces of the block 14 constructed and arranged to co-operate with the latter to mold or break down the feather. Above the beveled lower 105 portions of the opposite walls of the notch 110 42 said walls are inclined more sharply to the perpendicular, as indicated at 46, thus forming beveled faces which are inclined at the angle which it is desired to set the lip of 115 the sole. To enable the form 16 to be secured to its carrier the form is provided with an upstanding lug 48 which is notched at 50 to receive a screw 52 projecting forwardly 120 from the slide or carrier 20. The screw 52 is provided with a head arranged to overlap 125 the front face of the lug 48, a smooth shank portion for entering the notch 50 and a reduced shank portion which is threaded into the carrier 20. In attaching the form 16 to the carrier 20 the form is moved horizontally edgewise in a direction to engage the notch 50 with the smooth shank portion of the screw and insert the lug 48 between the front

face of the carrier 20 and the head of the screw 52. A horizontal rib 54 (Fig. 1) extends transversely across the front of the carrier 20 and is arranged to inter-engage with a horizontal groove of corresponding width in the rear face of the lug 48 to prevent twisting of the form 16 and insure that it will be maintained in a horizontal position with its feather and lip engaging faces parallel to the respective faces of the plate 14 and the form 18. The edgewise sliding movement of the plate 16 in the operation of attaching it to the carrier 20 is limited by means of a stationary bearing surface 56 (Fig. 4), hereinafter referred to, which serves accurately to locate the form 16 in proper vertical alinement with the plate 14 as well as to prevent the cylindrical carrier 20 from turning in its guideway. A latch 58 is pivoted at 60 to one side of a fixed guideway 61 in which the carrier 20 reciprocates and this latch is adapted to swing under the influence of gravity into a position determined by a stop screw 62 to co-operate with the bearing surface 56 to position the form 16 relatively to the carrier 20 and the plate 14 and detachably to hold said form in operative position. The head of the stop screw 62 overlaps the lower extremity of the latch 58 to hold the latch firmly against side thrust. The latch 58 may be swung by means of a handle 64 in a direction to free the lug 48 to permit convenient removal of the form 16. In this way the form 16 may be easily and quickly detached from its carrier without the necessity of loosening a nut, screw or like part. After the form 16 has been inserted in position upon the carrier 20 it may be held in place merely by allowing the pivoted latch 58 to swing into the operative position in which it appears in Fig. 3, thus avoiding the necessity of tightening a clamp device or the like.

The form 18 is arranged to co-operate with the form 16 to shape the lip of a sole to a desired predetermined contour. To this end the form 18, as best shown in Fig. 2, is provided with a rearwardly projecting, V-shaped portion adapted to engage the inner side of the lip and to co-operate with the upper faces 46 formed at opposite sides of the V-shaped notch 42 in the form 16 to shape the lip. For this purpose the converging edge faces of the V-shaped portion of the form 18 are inclined transversely at an angle corresponding to the angle of bevel of the faces 46 of the plate 16, thus providing lip shaping faces upon the form 18 which are complementary to the faces 46 of the form 16. The co-operation of the faces 46 with the complementary faces upon the form 18 insures that the lip of the sole will be inclined inwardly from a plane normal to the face of the sole. To insure that the inner form will engage the stock at the base of the lip, the under side of the form 18 is somewhat undercut or beveled, as indicated at 66. This construction insures that the edge of the form 18 will seat itself in any groove or channel which may be formed in cutting an inner channel flap in the process of forming a compound lip upon a sole and will facilitate the final operation of setting the lip by localizing the setting pressure exactly at the base of the lip.

In order that the form 18 may be readily removed from the carrier 22 so that it may be replaced by another form having a different contour the form 18 is provided with a transverse, dove-tailed tongue 68 which is received in a correspondingly shaped groove 70 in the lower portion of the carrier 22. To enable the form 18 to be quickly removed or inserted novel means is provided for locking the tongue 68 in the groove 70. This means comprises a horizontal lock bolt 72 which is slidably mounted in the carrier 22 above the groove 70, the bolt 72 extending transversely of the groove. At its rear extremity the lock bolt 72 is provided with a depending wing 74 adapted to enter a notch 76 (Fig. 2) in the rear side of the tongue 68 positively to locate the form 18 horizontally with respect to the form 16 and the plate 14 and securely to lock the form in place. The lock bolt 72 projects forwardly beyond the carrier 22 and is provided with a head 78 by which it may be manipulated for the purpose of disengaging the wing 74 from the notch 76. Normally, the wing 74 is yieldingly held in engagement with the notch 76 by means of a spring 80 which encircles the lock bolt 72 between the head 78 and the front face of the carrier 22. By pressing rearwardly upon the head 78 the wing 74 may be forced backwardly to disengage it from the notch 76, thus freeing the tongue 68 so that the form 18 may be readily disengaged from its carrier. As shown in Fig. 2, the rear edge face of the dove-tailed tongue 68 is curved at one side of the form 18, as clearly shown at 82 in Fig. 2. In the operation of slidably interengaging the tongue 68 with the groove 70 the curved portion 82 of the tongue first engages the wing 74 of the lock bolt and acts as a cam to slide the lock bolt rearwardly against the force of the spring 80, thus enabling the form 18 conveniently to be attached to the carrier 22 without the necessity of manually releasing the lock bolt.

The forms 16 and 18 are normally positioned in the same relation to each other and to the work table as are the corresponding forms disclosed in the patent hereinbefore referred to. As in the case of the outer form in the machine of said patent, the form 16 of the illustrated machine is normally positioned at a sufficient elevation above the work table to permit the insertion between the form and the work table of the feather

at the toe of the insole while at the same time the form 16 is near enough to the work table to enable the faces 46 at the opposite sides of the notch 42 to be engaged by the lip 5 of the insole as the latter is pushed rearwardly across the work table and block 14 by the operator. The form 16 thus serves as a gage to position the insole longitudinally with respect to the work table for the performance of the lip setting and feather molding operations, thus rendering it unnecessary to provide special gages or other positioning devices for this purpose. The form 18 is normally positioned somewhat higher 15 above the work table than the form 16 to facilitate the presentation of the insole to the latter.

To assist in shaping or molding the lip and the feather it is desirable to have the 20 shaping or molding instrumentalities heated. In the illustrated machine heat is supplied to the forms 16 and 18 by means of two stationarily mounted electric heating units 86 and 88, respectively (Fig. 4). As shown, 25 the unit 86 is in the form of a cylindrical block which is located in a socketed member 90 (see Fig. 5) secured to the exterior of the guideway 61, the member 90 having formed thereon the bearing surface 56 hereinbefore referred to which, in addition to locating the form 16 and preventing the carrier 20 from turning, provides also a contact face across which the vertical edge of the lug 48 rubs as the form 16 is raised and lowered so 30 that heat will be continuously conducted from the unit 86 to the form 16. The heating unit 88 also consists of a cylindrical block which is received in a socketed member 92 carried by a fixed bracket 94 in which the carrier 24 is mounted to slide. A smooth face 96, formed upon the member 92 at one side of the unit 88, engages the adjacent side of the slide 24 to insure continuous conduction of heat from the unit 88 through 35 the slide 24 and the carrier 22 to the form 18.

The movements imparted to the forms 16 and 18 are substantially the same as the movements imparted to the corresponding forms in the patent referred to. Briefly 40 described, the operative movements of these forms are as follows:—After the insole has been positioned on the work table by the engagement of the lip with the faces 46 of the form 16, both the form 16 and 18 are depressed until they are brought into pressing engagement with the insole, the form 16 engaging the feather of the insole adjacent to the point of the toe and the outer side of the feather, and the form 18 engaging the upper face of the insole between the converging toe portions of the lip. In the illustrated machine, however, on account of the angle of the complementary beveled faces 44 and 34 on the form 16 and block 14, respectively, the feather is offset or broken

down by the co-operation of the form 16 with the block 14 substantially as shown at 45 in Fig. 7. The form 16 is held against the feather under comparatively heavy pressure positively to break down the feather, 70 whereas the form 18 is initially held in engagement with the upper face of the sole under comparatively light pressure. After the forms 16 and 18 have been depressed into engagement with the insole the form 18 is 75 moved horizontally toward the form 16 to mold or shape the lip into the required contour. Thereafter additional pressure is applied to the form 18 to force the marginal portion of the beveled lower side of said 80 form firmly against the channeled portion of the insole at the base of the lip, this additional pressure causing the marginal portion of the form to apply heavy downward pressure exactly at the base of the lip. This 85 operation assists in setting the lip so that it will retain its molded contour. It will be seen by reference to Fig. 1 that when the final or lip-setting pressure is applied to the form 18 through the action of its actuating cam in the disk 28, not only will the feather continue to receive pressure from the form 16 but the pressure applied through the latter form will actually be increased.

From the foregoing it will be apparent that the feather will be molded or broken down at the toe of the insole and that the portion of the lip adjacent to the toe will be molded or shaped to a predetermined contour at what is practically a single operation. 100 The use of the illustrated machine obviates the necessity of performing an additional operation upon the insole for the purpose of offsetting the feather after the lip has been molded and set, and thus an additional handling of the insole and a considerable amount of time is saved in the manufacture of the insole.

As hereinbefore mentioned, forms of different shapes will be employed for insoles having differently shaped toes and accordingly provision has been made whereby the forms may be removed and replaced in a minimum amount of time and with a minimum amount of effort on the part of the operator. Each of the molding members may be secured in place in the machine by substantially a single movement and they are automatically positioned in accurate working relation to one another and effectively secured in place by the quick-detachable connections hereinbefore described.

In case it should be desirable at any time to shape and set the lip of an insole without offsetting or breaking down the feather this 125 result may be accomplished with the use of the illustrated machine by replacing the feather molding block 14 by a flat plate adapted to cover the entire surface of the work table, as indicated by dotted lines at 130

98 in Fig. 1, and by substituting for the form 16 a corresponding form having a feather-engaging face which is parallel to the plate 98.

5 Having described my invention, what I claim as new and desire to secure by Letters Patent of the United States is:—

1. In a machine of the class described, a form shaped to engage simultaneously throughout a substantial length of the feather and one side of the upstanding lip of a sole, and means for engaging the opposite side of the lip and co-operating with said form to shape the lip and to offset the feather from the plane of the sole.

2. In a machine of the class described, a member shaped to engage the feather and one side of a lip which has been raised above the plane of a sole, and means for engaging the opposite side of the lip and co-operating with said member to offset the feather and shape the lip while retaining the sole in a fixed position.

3. In a machine of the class described, a member shaped to engage the feather and one side of the upstanding lip of a sole simultaneously throughout a substantial distance along the margin of the sole, and means for engaging the opposite side of the lip from that engaged by said members and for co-operating with said member to shape the lip and break-down the feather while holding the sole stationary.

4. In a machine of the class described, means for engaging the feather of a sole, a member having molding faces integrally formed thereon and shaped to engage the lip of the sole simultaneously at both sides of the toe and co-operating with said means to offset the feather, and means movable relatively to said member for co-operating with said member to shape the lip.

5. In a machine of the class described, a form having a face for engaging the feather and a second face disposed in a predetermined fixed relation to the first face for engaging the lip of a sole, means co-operating with the feather-engaging face of said form to engage the feather simultaneously at both sides of the toe to offset the feather from the plane of the sole, and means for co-operating with the lip-engaging face of said form to shape the lip to a predetermined contour.

6. In a machine of the class described, co-operating forms for offsetting the feather of a sole from the plane of the body portion thereof, a member for setting the lip of the sole in an upstanding position, and means relatively to operate said forms to apply molding pressure to offset the feather and thereafter to operate the lip setting member and increase the pressure upon the feather.

7. In a machine of the class described, a support for a lipped sole, a member carried by the support for engaging the feather of a

sole upon the support simultaneously at both sides of the toe, a form constructed and arranged to co-operate with said member to mold the feather, a portion integral with said form for engaging the lip of the sole, and means movable relatively to said face for co-operating with the form to mold the lip of the sole.

8. In a machine of the class described, a support for a sole, a reciprocable form carried by the support having a face for engaging the feather of a sole upon the support and a second face disposed at an angle to the first face for engaging the lip of the sole, a member constructed and arranged to co-operate with the feather engaging face of said form to offset the feather from the plane of the sole, a second member constructed and arranged to co-operate with the lip-engaging face of the form to shape the lip, and interengaging devices on said support and said form for locating the form relatively to said member.

9. In a machine of the class described, a support for a sole, a form resting upon the support, said form having a plurality of locating apertures therein and a face for engaging the feather of a sole upon the support, means on the support for entering said apertures to locate said form relatively to said support, a cylindrical carrier, a guideway in which said carrier is slidable, a member on said carrier for co-operating with said face to mold the feather of the sole, means for detachably securing said member to said carrier, and a stationary bearing surface slidingly engaged by said member for locating said member relatively to said carrier and form and for preventing the carrier from turning in its guideway.

10. In a machine of the class described, a support for a sole, a form carried by the support for engaging the feather of a sole upon the support, a member constructed and arranged to co-operate with said form to bend the feather, and positioning members permanently attached to said support for locating the form relatively to said member and detachably securing the form in place.

11. In a machine of the class described, a form having two locating apertures therein and a surface for engaging the feather of a sole, means for co-operating with said form to break down the feather, a work support arranged to support said form and having members permanently attached thereto for entering said apertures to locate the form relatively to said means, said form being notched at each side of a line extending through said apertures to facilitate the introduction of a tool between the form and the surface of the work table for removing the form from said members.

12. In a machine of the class described, a form having locating apertures therein and

- a surface for engaging the feather of a sole, means for co-operating with said form to offset the feather, a work support arranged to support said form, and dowel pins fixed in said support for entering said apertures to locate the form relatively to said molding means.
13. In a machine of the class described, a work support having a portion for engaging the feather of a sole, a form for co-operating with said portion to mold the feather, a carrier for said form, fastening means on said carrier and form arranged to be interengaged by relative sliding movement of said parts, means for limiting said relative movement to locate said form in operative position, and a latch for detachably securing the form in operative position.
14. In a machine of the class described, a work support having a portion for engaging the feather of a sole, a form for co-operating with said portion to mold the feather, a carrier for said form, fastening means on said carrier and form arranged to be interengaged by relative sliding movement of said parts, means for limiting said relative movement to locate said form in operative position, and a latch for detachably securing the form in operative position.
15. In a machine of the class described, co-operating devices for molding the feather of a lipped sole, a form for co-acting with one of said devices for molding the lip of the sole, a carrier for said form, tongue-and-groove connections between the form and the carrier, and spring-pressed means constructed and arranged to hold said connections interengaged and to locate said form relatively to said co-operating devices.
16. In a machine of the class described, co-operating devices for molding the feather of a lipped sole, a form for co-acting with one of said devices for molding the lip of the sole, a carrier for said form, connections arranged to be interengaged by relative sliding movement between the form and carrier, a locking member normally maintained in operative position for locking the form to the carrier, and means for moving the locking member into inoperative position as said connections are being interengaged.
17. In a machine of the class described, co-operating devices for molding the feather of a lipped sole, a form for co-acting with one of said devices for molding the lip of the sole, a carrier for said form, tongue-and-groove connections between the form and the carrier, and spring-pressed means constructed and arranged to hold said connections interengaged and to locate said form relatively to said co-operating devices.
18. In a machine of the class described, a frame, a sole support having a portion for engaging the margin of a sole, a form movable relatively to said support for co-operating therewith to mold the sole margin, a carrier for the movable form, and a heated member in sliding surface engagement with said carrier for transmitting heat thereto and for locating said form relatively to said support.
19. In a machine of the class described, a frame, a sole support having a portion for engaging the margin of a sole, a form movable relatively to said support for co-operating therewith to mold the sole margin, a carrier for the movable form, a stationary heated member in sliding surface engagement with said carrier for transmitting heat thereto, and means co-operating with said member for locating said form relatively to said carrier.
20. In a machine of the class described, a frame, a sole support having a portion for engaging the margin of a sole, a form movable relatively to said support for co-operating therewith to mold the sole margin, a carrier for the movable form, a heated member in sliding surface engagement with said form for transmitting heat thereto and means co-operating with said member for detachably securing said form to said carrier.
21. In a machine of the class described, a frame, a table carried thereby for supporting a sole, co-operating forms for molding the lip of the sole, movable carriers for each of said forms, a stationary bearing face arranged to be slidably engaged by one of said carriers and to locate the respective form relatively thereto, a stationary bearing face arranged to be slidably engaged by the other of said carriers, and a heating unit located in close proximity to each of said bearing faces.

In testimony whereof I have signed my name to this specification.

JOHN W. COSGROVE.
